UNITED STATES PATENT OFFICE.

JAMES D. DAVIS, OF LOS ANGELES, CALIFORNIA.

COMBINATION CANE AND SUNSHADE.

Application filed January 21, 1926. Serial No. 82,782.

This invention relates to sunshades for lawns, beaches and the like, and has for one of its objects the provision of a novel, simple and inexpensive device of this character which shall be comparatively light in weight and will when folded have the appearance of a cane and which can be easily and quickly erected and firmly supported in position for use.

10 A further object of the invention is the provision of a sunshade of the character stated which shall include an awning, supports therefor, and means for connecting the awning to and between the supports in a manner to permit it to be turned about a horizontal axis so as to enable the person using the device to be effectively shielded from the rays of the sun.

20 A further object of the invention is the provision of a sunshade of the character stated wherein portions of the supports are adapted to be connected to provide an imitation cane case for the reception of the other portions of the supports and the awning.

25 With the foregoing and other objects in view, which will appear as the description proceeds, the invention consists of the construction, combination and arrangement of parts hereinafter fully described and claimed, and illustrated in the accompanying drawing, wherein:

Figure 1 is an elevational view of the sunshade in condition for use,

25 Figure 2 is a top plan view of the sunshade when in condition for use,

Figure 3 is a sectional view taken on a plane extending centrally and longitudinally through the folded sunshade, and

40 Figure 4 is a sectional view taken on the plane indicated by the line 4-4 of Figure 3.

Corresponding and like parts are referred to in the following description, and designated in the several views of the accompanying drawing, by similar reference characters.

45 The sunshade comprises upright supports 1 which are adapted to be embedded in the ground, and an awning 2 which is secured to and between the supports 1. The supports 1 are similar and of sectional formation, and the lower sections 3 and upper sections 4 thereof are detachably connected together. The lower sections 3 are provided with pointed lower ends 5 to permit them to be readily driven into the ground. The upper sections 4 are provided in their lower

ends with axial bores or recesses 6 for the reception of the upper end portions of the lower sections 3 whereby to detachably connect the sections together. The upper sections 4 are provided above the bores or recesses 6 with axial bores or recesses 7 which are considerably longer than the bores or recesses 6 and into which the lower sections 3 are inserted so as to reduce the length of the supports 1 when it is desired to fold the sunshade. Tubular members 8, which constitute a case for the folded sunshade, are embedded for a portion of their length in the ground about the lower sections 3 so as to maintain the supports 1 in upright position. One of the members 8 has externally screw threaded ends 9 and 10 and the other has an externally screw threaded end 11 and an internally screw threaded end 12.

50 The awning 2 which may be made of canvas or other suitable flexible material, is secured at one end to a roller 13 and has secured to its other end a stretcher bar 14. Rings 15 which are removably applied to the support sections 4 and have sufficient frictional contact therewith to hold them against casual movement, and flexible members or straps 16 which are secured to the rings 15 and detachably connected to the awning 2 by hooks 17, constitute the means for connecting the awning 2 to the supports 1. As the members 16 are flexible, the awning 2 may be turned about a horizontal axis so as to enable it to be moved into and supported in a position where it will most effectively shield the person using the device from the rays of the sun. The means by which the awning 2 may be adjusted and secured in adjusted position, comprises rings 18 and 19 and flexible members or straps 20 and 21 connected to the rings. The rings 18 and 19 are mounted upon one of the support sections 4 for adjustment longitudinally thereof and with respect to each other, and the members 20 and 21 are detachably connected to the awning 2 by hooks 22. The rings 18 and 19 have sufficient frictional contact with the support sections 4 to hold them against casual movement with respect to each other and said section.

55 The sunshade may be readily erected, and when erecting the same the tubular members 8 are driven into the ground for a portion of their length. The support sections 3 are then passed through the tubular members 8 and driven into the ground for a short

distance below the lower ends of the tubular members 8 in such a manner that they will contact with the inner sides of said members. The support sections 4 are then mounted on the support sections 3; and thereafter the awning 2 is connected to the support sections 4. The awning 2 may be adjusted into the desired position by moving the rings 18 and 19 with respect to each other, and the awning 2 may be supported at the desired height from the ground by adjusting the rings 15, 18 and 19 on the support sections 4. When it is desired to fold the sunshade, the awning 2 is detached from the support sections 4, said sections are removed from the support sections 3, and said last named sections and the tubular members 8 are withdrawn from the ground. The awning 2 is wound about the roller 13, the support sections 3 are inserted in the recesses 7 of the support sections 4, and the threaded ends 9 and 11 of the tubular members 8 connected by a coupling 23. The connected tubular members 8 provide a case for the reception of the folded awning 2 and collapsed supports 1, and this case is provided at one end with a ferrule 24 and at the other with a handle 25 in order that it may have the appearance of a cane. The ferrule 24 is threaded in the end 12 of one of the tubular members 8, and the handle 25 is threaded on the end 10 of the other of these members.

From the foregoing description, taken in connection with the accompanying drawing, the advantages of the construction of the sunshade will be readily apparent to those skilled in the art to which it appertains. While I have described the principle of the invention, together with the device which I now consider to be the best embodiment thereof, I desire to have it understood that the device shown is merely illustrative, and that such changes may be made when desired as are within the scope of the invention as claimed.

What is claimed is:—

1. A sunshade of the character set forth, comprising supports each embodying detachably connected sections, a flexible awning, means detachably connecting the flexible awning to the supports, and reinforcing members for said supports adapted to be connected together to form a case for the awning and supports.

2. A sunshade of the character set forth, 55 comprising supports, reinforcing members for said supports, and an awning connected to the supports, said members being hollow and adapted to be connected together to provide a casing for the supports and awning. 60

3. A sunshade of the character set forth, comprising supports, an awning, means connecting the awning to the supports for adjustment about a horizontal axis, rings mounted on one of the supports for adjustment in the direction of the length thereof and with respect to each other, the rings having sufficient frictional contact with the support to hold them against casual movement with respect thereto, and elements connected to the rings and awning, said rings and elements providing means by which the awning may be adjusted and secured in adjusted position. 70

4. A sunshade of the character set forth, 75 comprising supports, an awning, means connecting the awning to the supports for adjustment about a horizontal axis and embodying rings removably applied to the supports and having frictional contact therewith and members connected to the rings and awning, other rings mounted on one of the supports for adjustment in the direction of the length thereof and with respect to each other, the other rings having sufficient frictional contact with the supports to hold them against casual movement with respect thereto, and elements connected to the other rings and awning, said other rings and elements providing means by which the awning may be adjusted and secured in adjusted position. 85

5. A sunshade of the character set forth, comprising supports, an awning, means connecting the awning to the supports for adjustment about a horizontal axis, said means being connected to the supports for adjustment in the direction of the length thereof, members mounted on the supports for adjustment in the direction of the length thereof and with respect to each other, and elements connected to said members and awning, said members providing means by which the awning may be adjusted about said axis and secured in adjusted position. 95 100 105

In testimony whereof I affix my signature.

JAMES D. DAVIS.
